UNITED STATES PATENT OFFICE.

FREDERICK S. FRYE AND EDWARD WADE, OF LAWRENCE, MASSACHUSETTS.

APPARATUS FOR BALLING WARPS.

SPECIFICATION forming part of Letters Patent No. 373,180, dated November 15, 1887.

Application filed October 16, 1886. Serial No. 216,456. (No model.)

To all whom it may concern:

Be it known that we, FREDERICK S. FRYE and EDWARD WADE, citizens of the United States, residing at Lawrence, in the county of 5 Essex and State of Massachusetts, have invented certain new and useful Improvements in Apparatus for Balling Warps; and we do hereby declare the following to be a full, clear, and exact description of the invention, such 10 as will enable others skilled in the art to which it appertains to make and use the same, reference being had to the accompanying drawings, and to letters or figures of reference marked thereon, which form a part of this 15 specification.

This invention relates to "balling-machines," so called, and particularly that class employed in making up warps.

The said invention consists, chiefly, in the 20 combination of a pulley and its support with a ball-shaft, means for imparting motion to said shaft, a creel or stand, and a guide through which the warp-threads from the spools of the creel and the warp-threads from a previously- 25 wound ball first passed around said pulley may pass together, said pulley serving to reverse the direction of the warp-threads coming from said previously-wound ball, substantially as set forth.

30 The drawings accompanying this specification represent, in Figure 1, a side elevation of an apparatus for reducing to practice and embodying our invention, and is composed of three essential and primary parts—a creel and 35 warp-guides, an intermediary post, and the winding mechanism. Fig. 2 represents a front elevation of the winding mechanism, while Figs. 3 and 4 are respectively a side and front elevation of the intermediary post.

40 At A is represented the stand, which contains the spools *a a*, the individual warp ends from which are properly distributed and passed through the reeds *b b* over and about the intermediate rollers, 1 2 3, mounted in the stand- 45 ards B B, which constitute the warp-guiding devices C as an entirety. Thence the warp ends are passed to a vertical post, D, securely affixed to the floor centrally of and in front of the warping-machine, the top of said post 50 being surmounted by a condensing-tube, *c*, which is open at the top and provided with curved lips *d d* to permit of ready removal

from or introduction of the warp ends from or within said tube. By means of this tube the various warp ends emanating from the spools 55 and which pass through the warp-guides are converged and massed to form the "warp," so called. (Shown at E.) Below the condensing-tube *c*, in vertical alignment therewith and secured likewise to said post D, is a guide 60 or pulley, *e*, suitably journaled and disposed upon the post in front of a longitudinal aperture, F, formed in the latter. The said post, therefore constitutes a support for said pulley. This pulley and aperture co-operate 65 to permit the direction of the warp passing through the post to be reversed and changed, for purposes hereinafter described. From the condensing-tube *c* the warp ends, now in a compact body and forming the warp as an entirety, are passed to the winding apparatus. 70 This latter is shown as composed of a frame, G, resting upon twin standards or housings H H.

Longitudinally disposed and in horizontal 75 adjustment with each other are two rollers, I I, while resting upon the latter and axially aligned therewith is a winding-shaft, J, upon which is formed the ball. Said shaft is journaled in slotted standards K K, and thereby 80 is capable of vertical movement caused by the continued and gradual increase in the size of the ball L, due to the laying of the warp thereon. Furthermore, said slots answer a second purpose—that is, they permit of ready 85 removal of the ball from the machine when it is so desired. The requisite tension, and consequently the compactness with which the warp is laid upon the winding-beam, is regulated by means of anti-friction rolls *f f*, which 90 rest upon each end of the ball-shaft. Said rolls are secured in frames M M, through the lower parts of which are inserted straps *g g*, and these latter connect with levers N N, weighted and pivoted to brackets affixed upon 95 the standards H H.

Rotary movement of the ball-shaft or winding-beam is effected by means of the rollers I I, mounted upon shafts *i i*, to the extremities of which are affixed gears *h h*, meshing with 100 the gears *j k*. These latter are disposed upon the main shaft *l*, operated by the pulley O, actively induced by some prime motor.

In the formation of the ball, and to enable

the warp ends or warp E as it passes on and about the winding-beam to reciprocate or traverse the length of the beam, and thus lay the said warp on the ball evenly from one end to the other, we have provided a stationary guide-rod, P, fixed in the frame G, and which is to support a warp guide, Q, consisting in the present instance of a sleeve provided with a vertical arm bifurcated at its end, and through which the warp is passed as it travels onward in the act of being laid upon the beam to form the ball. Right line reciprocations or traverses of this guide Q are effected by means of a vertically-disposed downwardly-projecting prong or arm, which successively engages two oppositely-cut spiral slots in the periphery of the shaft R. The latter is rotated by means of a gear mounted upon it and meshing with a similar gear upon the main shaft L. The former gear is marked w, and the latter gear is marked w'.

The mechanism above described for causing traverses of the guide Q is well known, and has long been employed in winding mechanisms of various kinds.

By means of the above apparatus a ball of any diameter and containing any number of warp ends may be produced from one set of spools.

The operation is as follows: Presuming the warp E contains six hundred warp ends, and that the desired warp shall contain twelve hundred warp ends, we proceed as follows: When the requisite length of warp has been laid upon the winding-shaft to form the ball L, the entire apparatus is stopped. The ball L is now removed and placed beneath the machine, and is now designated as L' and rests upon a carriage, S, preferably mounted in guides and movable upon the floor. The warp E, without being cut, is now doubled, and the end so formed is entered in the direction of arrow 1, Fig. 3, through the aperture F, when the warp is passed about and around the pulley e, preferably grooved; thence it is returned and secured to an empty winding-shaft, J. Proper tension upon the ball L' is now secured by a weighted brake-beam, T, pivoted to and beneath the rectangular frame G. In this way two warps are provided from the same spool-stand, and when the winding mechanism is

again set in motion a warp, L², containing twelve hundred warp ends, is now produced, and is laid upon the winding-shaft J in the form of a ball. One-half of these ends emanate from the warp-guides and stand of creels while the other half are obtained from the ball L', now in process of unwinding, the warp passing outwardly therefrom to the pulley e, about which it passes, whereby the direction in its path of travel is changed and it is returned to merge and unite with the warp coming from the creels, thereby forming an integral compact warp in the present instance of double the number of warp ends as there are creels in the stand.

If necessary, the number of warp ends may be increased to any desired extent by the employment of one or more balls to be unwound after the manner above described and to be united with the warp emerging from the warp-guides. Moreover, by the employment of the groove-pulley e and post D the ball L' can be snugly placed beneath the winding-machine, floor-space is economized, and the mechanism for operating said ball is near at hand and can easily and readily be applied thereto.

We claim—

1. The combination of a pulley and its support with a ball-shaft, means for imparting motion to said shaft, a creel or stand, and a guide through which the warp-threads from the spools of the creel and the warp-threads from a previously-wound ball first passed around said pulley may pass together, said pulley serving to reverse the direction of the warp threads coming from said previously-wound ball, substantially as set forth.

2. The combination of post D and the pulley e, and condensing-tube c, mounted thereon, with the guide Q, the spool-carrying shafts J S, and means for rotating the former and supporting the latter shaft, substantially as and for the purpose set forth.

In testimony whereof we affix our signatures in the presence of two witnesses.

FREDERICK S. FRYE.
EDWARD WADE.
